CLAIM

The ornamental design for a temple for eyeglass frame, as shown and described.

DESCRIPTION

FIG. 1 is a right side elevational view of a temple for eyeglass frame showing my new design; the broken line showing of part of the front of the eyeglass frame in FIGS. 1-4 is for illustrative purposes only and form no part of the claimed design;

FIG. 2 is a left side elevational view thereof;

FIG. 3 is a top plan view thereof;

FIG. 4 is a bottom plan view thereof;

FIG. 5 is a rear elevational view thereof; and,

FIG. 6 is a front elevational view thereof.

FIG. 1

FIG. 2

FIG. 3

FIG. 4
